PERFORATING ATTACHMENT FOR
PRINTING PRESSES

Samuel Meckler, St. Paul, Minn.

Application March 21, 1932. Serial No. 600,143

2 Claims. (Cl. 164—98)

My invention relates to a new and useful scoring and perforating device adapted for use simultaneously with the printing process of such presses.

5 The main object is to provide a device for positively and efficiently perforating paper run through a printing press, said perforating means adapted to be mounted in a chase in proper predetermined position relative to the type mounted 10 in the chase in the usual manner well known in the printing field. A further object is to produce scoring or perforations which are clear and not inked, a feature hitherto not accomplished as far as I am aware. Other objects and advantages 15 of my device are hereinafter fully set forth and illustrated in the accompanying drawing, in which,—

Fig. 1 is a partly perspective front view of a printing press with one of my perforating devices 20 in operative positions, only such parts of the press being shown as are deemed necessary for a clear understanding of the device.

Fig. 2 is a face view of one of my perforating devices in a preferred form.

25 Fig. 3 is a longitudinal sectional view as on line 3—3 in Fig. 2, and including a platen 9.

Fig. 4 is a detail view of the left hand end portion of Fig. 3 with the perforation blade in actual contact and making a row of perforations in a 30 sheet of paper.

Fig. 5 is a cross sectional view as on line 5—5 in Fig. 4 but modified to show a scoring blade instead of a perforating blade.

Referring to the drawing by reference numerals, I have illustrated in Fig. 1 such parts of a press pertaining to the use of my device and will be readily understood to any one familiar with press construction.

6 is the ink distributing plate for the usual 40 inking rollers (not shown) reciprocable over its surface, said rollers inking the type, designated 7, fixed in the usual manner in a quadrangular chase 8. 9 is the main platen on a sheet of paper 10 and is retained by grippers 11 while the type 45 is brought into contact with the paper. Obviously the type area is within or between the grippers 11.

My device comprises an elongated metal bar 12 of suitable length, said bar being actually a deep channel bar with an elongated central slit or 50 opening 12A extending inwardly from its face to a bottom 12B and to integral end walls 12C. In Fig. 1 such bar is shown mounted horizontally in chase 8 and over a certain area of type 7 both retained removably in the chase by the wedge like blocks 13 well known to printers. The depth of

bar 12 is less than the height of the type, the face of said type being indicated by dotted lines 14 in Fig. 3 in which the type is approaching the paper 10 downwardly.

Within the slot 12A is reciprocably retained a 60 smaller and likewise slotted bar 15 having integral solid end walls 15C and an outwardly opening slit 15A in which is rigidly and removably retained a blade 16 by means of set screws 17. The exposed edge of this blade normally protrudes from the 65 inner bar beyond and parallel to the face of the main bar as clearly illustrated at B in Fig. 3 but not as far out as the face of the type (14); said edge for perforation purposes comprising a line of prongs or serrations designated S. The just 70 described parts are assumed to be initially in the relative retracted positions shown in Fig. 3, bar 15 bearing inwardly against bottom 12B of the main bar 12.

At each end wall 12C is provided a reciprocable shoe member 18 each slidably bearing against the inner surface of its wall 12C and having an exterior enlargement or foot 18F inwardly of which it consists of a straight shank. Interposed between each cam and the adjacent 75 end of inner bar 15 is pivotally mounted at 19 a rocking cam member 20 each having a beam lever action on its pivot 19 which is fixed in the side walls of main bar 12. The tapered inner end of each of said rock member or cam 20 contacts 80 loosely, and both simultaneously in slight depressions or notches 21 of a shoe 18 and the end wall 15C of inner bar 15. The outer end of each cam is also reduced and formed with an integral knob 20K adapted to engage loosely in 85 an inwardly opening cavity 18K of the adjacent shoe. The shoes 18 project outwardly normally from the face of bar 12 and are pressed or impelled outwardly each by suitable spring means such as a coil spring 22. Obviously this outward 90 pressing of the shoes keeps the members 20 in the inclined positions shown in Fig. 3 and the bar 15 is retained in innermost retracted position in bar 12.

In said Fig. 3 the bar is assumed to be pressing 100 down toward a paper 10 to be printed. The springs 22 hold the shoes 18 in projected position and the bar 15 simultaneously retracted by means of the cam members 20. The shoes 18 contact first with the grippers 11 or correspond- 105 ing members, the type in the chase continue down toward the paper. Obviously as the type move down with bar 12 the shoes 18 are pressed inwardly rocking the cam 20 simultane- 110 ously and the said latter rocking movement pro-

jects the perforation member 15 and its blade 16 toward and into the paper 10 in spaced relation to the printed area as required. The contact of the perforator blade with the paper is 5 clearly illustrated in Fig. 4.

The cavity 18K of the shoe 18 has end clearance for part 20K of the cam 20 and likewise the grooves 21 are deep enough to provide end clearance for the inner end of the cam (see Fig. 10 4) during arcuate movement of the opposite ends of each cam while the bar 15 is pressed into or pressed back from perforating contact.

It is now also obvious that after the perforation action and simultaneous printing has taken 15 place the press opens and the shoes 18 are released from contact, springs 22 pushing them outwardly and the perforation bar 15 is retracted into bar 12 to original position, levers 20 being rocked by the spring action and sliding movement of 20 the cam or shoe members 18 and directly causing bar 15 to be retracted.

With the parts in their original positions described, the serrations S are normally inward of the plane 14 of the type faces and the inking 25 rollers consequently do not touch the edge of blade 16 which is therefore positioned so as to make clear perforations in the paper when projected as in Fig. 4. In Fig. 5 the outer edge S' of the blade 16 is shown as a knife edge (beveled) to provide for scoring of paper instead of 30 perforations.

In Fig. 1 the dotted lines 12X indicate a transverse position of my perforation bar within the 35 chase 8 in which case blocks 23 suitably spaced near the edges of paper 10 are placed on the platen 9 to be contacted by the shoes 18 in the manner previously described herein.

The invention in a preferred form and modification have now been fully disclosed. It will 40 be understood that other modifications may be embodied without departing from the scope and spirit of the invention. These perforation and scoring devices may be provided in various lengths and any number of them may be clamped 45 within a chase in required formation to provide parallel or angular scoring and perforation or

combinations thereof for folding purposes or severing of the printed sheet.

I claim:

1. A perforation device for printing presses having a platen, grippers adapted to press paper on the platen, a type chase and friction means for retaining set-up type in the chase; said perforation device comprising an elongated main bar of quadrangular form in cross section, the height of said main bar being less than the height of the type, said main bar being provided with an elongated deep slot intermediate its ends, an elongated secondary bar reciprocable within said slot and its ends terminating in spaced relation to the ends of the slot, spring actuated means normally holding said secondary bar retracted toward the bottom of the main bar, in said slot, an elongated perforation blade removably secured in said secondary bar and having a serrated edge protruding therefrom, said spring actuated means comprising a pair of protruding contact members one in each end of the slot and spring means normally pressing said members outwardly from the main bar, said protruding contact members adapted to contact yieldingly 100 each on the face of a gripper, and means actuated by said contact members to reciprocate the secondary bar outwardly and cause its perforation bar to perforate paper on the platen, said means actuated by the contact members comprising rocker-cams pivotally mounted in the main bar intermediate each contact member and the adjacent end of the secondary bar, the outer ends of each such cam engaging a contact member and the opposite end loosely engaging a notch 110 in the adjacent end part of the secondary bar, the yielding inward movement of each contact member causing a rocking action of its cam to project the secondary bar as described.

2. The structure specified in claim 1, in which 115 the spring means which normally presses the contact members outwardly from the main bar comprises a compression coil spring interposed between the inner end of each contact member and the bottom of the groove in the main bar. 120
